UNITED STATES PATENT OFFICE.

CLEMENT C. BURKHARD, OF KASHIWA, NEW YORK.

SWITCH-BOX HOLDER.

Application filed November 26, 1921. Serial No. 314,083.

This invention relates to switch box holders.

It is a well known fact that when switch boxes are arranged on plaster board walls or the like, the character of the material is such that the box cannot be nailed or suitably secured to the wall, and frequently necessitates the positioning of the box at an inconvenient location on the wall, in order that the box may be arranged in juxtaposition to the studding so that the box can be supported thereon.

It is therefore the chief characteristic of the present invention to provide a switch box holder which can be quickly and conveniently associated with the box to support the latter at any particular location on the wall, without the use of nails or other analogous fastening elements.

It is also the purpose of the invention to design a switch box holder which possesses the desired features of simplicity, and one which can be manufactured and sold at a very nominal cost.

The nature and advantages of the invention will be better understood when the following detailed description is read in connection with the accompanying drawings, the invention residing in the construction, combination, and arrangement of parts as claimed.

In the drawings forming part of this application, like numerals of reference indicate similar parts in the several views and where-

in:

Figure 1 is a front elevation of the switch box, showing the same mounted upon a wall.

Figure 2 is a view looking at the rear of Figure 1.

Figure 3 is a sectional view taken on line 3-3 of Figure 1.

Figure 4 is a similar view taken on line 4-4 of Figure 1.

Figure 5 is a view in elevation, showing the holder collapsed.

Referring to the drawings in detail, 10 indicates a fragmentary portion of a wall, 11 the switch box which is provided with lugs 12 which project from the ends of the box to bear against the outside of the wall when the box is inserted through the opening 13 formed in the wall for the reception of the box.

The holder forming the subject matter 55 of the present invention embodies two bowed levers indicated at 14, the corresponding

branches of which levers are crossed and pivoted as at 15. The other corresponding branches of these levers terminate to provide hooks 16. The levers when in position 60 for use unitedly define what may be termed a yoke clearly illustrated in Figure 3. Associated with each lever is a substantially U-shaped resilient element indicated at 17, and that side of each element associated with 65 the adjacent lever also terminates to provide a hook 18. The resilient elements are considerably larger than the yoke defined by the levers 14, and the free ends of said elements terminate to provide rounded surfaces 70 or loops 19 which will prevent said elements from puncturing or otherwise injuring the wall of the building, should the wall be made of plaster or other analogous material.

In practice, the wall 10 is provided with 75 the opening 13 for the reception of the switch box 11, and this opening is made slightly wider than the width of said box.

When the box has been inserted through the opening, the lugs 12 bear against the outer side of the wall as clearly illustrated in Figure 1.

One of the holders above described is then collapsed in a manner illustrated in Figure 5, and the holder passed through the opening 13 at one side of the 80 box 11.

When the hooks of the holder are brought into juxtaposition to the edge of the box, the crossed extremities of the levers are depressed, thereby extending the levers to the position illustrated in Figure 3 and 85 causing the hooks to snap over the adjacent edge of the box.

During this movement of the levers, the rounded or looped extremities of the resilient elements which bear against the inner side of the wall are placed 90 under tension, the tension being sufficient to hold the box rigidly positioned upon the wall.

The holder at the opposite side of the box is arranged in the same manner. With the device arranged as shown in the draw- 100 ing, the hooks 16 and 18 engaging the top and bottom walls of the box exert a pressure on the supporting element and thereby firmly hold the latter against the wall or other surface to support the box. This is 105 due to the fact that the hooks 16 and 18 are disposed at a greater distance apart when the parts are expanded than the distance between the top and bottom walls of the box.

Manifestly, the switch box can 110 be mounted upon the wall at any desired location, and in the most convenient posi-

tion, inasmuch as nails or other analogous fastening elements are not used for associating the box with the wall structure. In order to remove the box from the wall it is only necessary to engage a screw driver or the like under the hooks and raise the hooks, which will cause the holder to collapse so that it can be quickly and easily removed.

While it is believed that from the foregoing description the nature and advantages of the invention will be readily apparent, I desire to have it understood that I do not limit myself to what is herein shown and described, and that such changes may be resorted to when desired as fall within the scope of what is claimed.

What I claim is:—

1. A switch box holder comprising a yoke having curved pivotally connected sections, free to rotate about the pivot with respect to each other in one direction, and limited in their rotation in the other direction, resilient elements carried by the respective sections of the yoke and curved in the same direction with the latter, and hooks formed at the point of juncture of the yoke sections with said elements, each hook engaging one side wall and the adjacent end wall of the box, said hooks being spaced a greater distance apart than the distance between the walls of the box for the purpose specified.

2. A switch box holder of the character described comprising a yoke including two pivotally connected sections, free to rotate about the pivot with respect to each other in

one direction, and limited in their rotation in the other direction, substantially U-shaped resilient elements carried by each section of the yoke and curved in the same direction therewith, hooks formed by the yoke sections and said elements at their point of juncture, with said hooks arranged to engage the same side wall and opposed end walls of the box, and spaced a greater distance apart when extended for use than the distance between said end walls.

3. The combination with a support having a opening, and a switch box arranged in said opening, of a holder for said box comprising a yoke including pivotally connected sections, free to rotate about the pivot with respect to each other in one direction, and limited in their rotation in the other direction, resilient elements supported by the sections of the yoke and curved in the same direction therewith, and adapted to be passed through said openings with their free ends engaging the inner side of said support, said elements being placed under tension when said yoke is arranged in position for use, hooks formed at the point of juncture of the yoke sections and said resilient elements, said hooks engaging one side wall and the opposed end walls of the box and spaced a greater distance apart when the yoke is extended for use than the distance between said walls of the box for the purpose specified.

In testimony whereof I affix my signature.

CLEMENT C. BURKHARD.
